UNITED STATES PATENT OFFICE.

GEORGE JACKSON, JR., OF HOHOKUS, NEW JERSEY.

SIGNAL APPARATUS.

1,221,538.

Specification of Letters Patent.

Patented Apr. 3, 1917.

Application filed February 26, 1915. Serial No. 10,697.

To all whom it may concern:

Be it known that I, GEORGE JACKSON, Jr., a citizen of the United States, residing at Hohokus, in the county of Bergen and State of New Jersey, have invented certain new and useful Improvements in Signal Apparatus, of which the following is a specification.

My present invention is an improvement upon the railway signal apparatus disclosed by my Letters Patent No. 1100243, and it has for its objects, first, so to construct the apparatus as to prevent the disturbance of the signal circuit under certain conditions to be hereinafter pointed out; and, secondly, to render the apparatus more sensitive and responsive to the contemplated actuating influence. In general, the object of the present invention is to increase the efficiency and reliability of the apparatus.

Referring to the accompanying drawings,

Figure 1 is an isometric view showing my invention applied to a single-track railway system; and

Fig. 2 is a diagram of the apparatus.

The railway track and intersecting street, road or the like to be protected are respectively indicated by the characters *a* and *b*. The source of current for operating the apparatus in the present instance consists of conductors including the "feeder" *c* and trolley wire *d*, supported by poles *e*.

1, 2 and 3 designate a set of contacts arranged at each side of the intersection of the track and street, and 4 is another contact arranged at or near said intersection, such contacts being disposed in such proximity to the wire *d* that the intervening space between any of them and the wire 40 will be electrically bridged by the trolley wheel *y* of a vehicle passing over the railway.

The foregoing elements are or may be all substantially the same as in my patent aforementioned.

As in my said patent also, so in the present case, with certain exceptions to be noted, the conductor *h* extending from the feeder *c* and including the switch *A* for closing the circuit via this conductor and one (*h'*) of its branches *h' h''* to ground, said branches respectively including the cores and windings of magnets *B' B''*, normally closed switches *C' C''*, and the signal *f g* and a 55 fuse and snap switch *x*; the branches *i' i''* of a conductor *i*, said branches extending from

the contacts 2 2 and said conductor *i* including the magnet *D'* and being grounded by being connected with *h''* between *C''* and *x*; the branches *j' j''* of a conductor *j*, said branches extending from the contacts 1 1 and said conductor *j* including the magnet *D''* and being connected with branch *h''* between switch *C''* and *x*; the branches *k' k''* of a conductor *k*, said branches extending from 65 the contacts 3 3 and said conductor *k* including the magnet *E''* which has the switch *C''* for its armature and being connected with conductor *j* between *D''* and *h''*; the conductor *l* extending from the contact 4 70 and including the magnet *E'* and being connected with conductor *i* between *D'* and *h''*; and the resistances *R* in the conductors *h''* and *j*, one between *x* and the point where *i* joins *h''* and the other in *j* between where 75 *j* joins *h''* and *k* joins *j*, are or may be all substantially the same as in my aforesaid patent.

In the present case, however, there is included in the branch *h''* the auxiliary switch *A'*, which, like switch *A*, is pivotally connected with conductor *h* and forms part of its branch *h''*. Each of the wires *i* and *j* has a break therein whose terminals *w' w'* and *w w* afford rests which normally 85 support the switches *A A'* in the positions shown in Fig. 2, plates *u u'* on said switches *A A'* (and insulated therefrom) bearing against said rests or terminals and closing the circuits through *i* and *j*.

When a passing vehicle has set the signal *f g* by closing the circuit *i' i* at, say, the left-hand contact 2, so that switch *A* is held by magnet *B'* in the position to close circuit *h h'* and leave circuit *j* open at *w w*, then closes 95 the circuit *j* at the left hand contact 1, magnet *D''*, instead of being energized, is completely uninfluenced to attract switch *A'*, because circuit *j* is open at *w w*; when, however, the circuit *l* is closed at 4 and *C'* is 100 attracted by *E'* and the signal circuit *h h'* is thereby broken and, magnet *B'* being de-energized, switch *A* closes the circuit *j*, and when the circuit *j* is next closed by the vehicle at the right hand contact 1, said circuit being now closed at *w w* by plate *u*, magnet *D''* is energized and attracts *A'*, closing the circuit *h h''* at *A' B''* so that 105 *B''* continues to maintain circuit *i* open at *w' w'* while the vehicle passes right hand contact 2, thereby preventing the signal from being set. It will be understood that 110

on the vehicle now passing right hand contact 3 circuit h will be closed and E'' being energized C'' will break the circuit h h'' , and B'' being thereby deenergized A' will 5 assume its normal position, leaving the several parts *in statu quo*.

My present arrangement, it will thus be apparent, avoids completely any possibility of disturbance of the signal circuit by the closing 10 at the relatively first contact 1 of the circuit of the means to render inactive the signal actuating means, because the latter circuit at that time is broken at another point, *i. e.*, w w u . It involves the further important advantage 15 that both the switch A and the switch A' may normally be made to rest relatively close to the cores of the attracting magnets D' and D'' , respectively, which condition was necessarily absent in my patented system where the single switch A had to have appreciable movement from magnets D' B' to magnets D'' B'' so that the power of D' , for instance, would not prevail over B'' when the relatively first contact 1 was 20 passed by the vehicle and so prematurely cause the signal to be suppressed.

Having thus fully described my invention, what I claim as new and desire to secure by Letters Patent is:—

30 1. In combination, a railway, a vehicle movable thereover and having a circuit closer, a source of current having a conductor extending along the railway, a signal, a conductor h leading from the source conductor and having grounded branches h' h'' , said branches respectively having normally open circuit-closing switches A A' both connected with conductor h and branch h' containing said signal, means to control the 35 closing and opening movements of switch A including a grounded magnet-including conductor i having contacts 2 2 spaced from each other lengthwise of and arranged in circuit-closer-bridging relation to the source-conductor, and also including a grounded magnet-including conductor l having a contact 4 between contacts 2 2 and in circuit-closer-bridging relation to said source-con- 40 ductor, and another magnet-including conductor j controlling switch A' and having contacts 1 1 between contacts 2 2 and each side of contact 4 and in circuit-closer-bridging proximity to said source-conductor, conductors i and j having breaks normally closed by switches A' and A , respectively. 45

2. In combination, a railway, a vehicle movable thereover and having a circuit closer, a source of current having a conductor extending along the railway, a signal, a conductor h leading from the source-conductor and having grounded branches h' h'' , said branches respectively having normally open circuit-closing switches A A' both connected with conductor h and branch h' containing said signal, said branches further 50 having normally closed breaks c' c'' therein, respectively, means to cause closing movement of switch A including a grounded magnet-including conductor i having contacts 2 2 spaced from each other lengthwise of and 55 arranged in circuit-closer-bridging relation to the source-conductor, means to break branch h' at c' including a grounded conductor l having a contact 4 between contacts 2 2 and in circuit-closer-bridging relation to 60 said source-conductor, 65 means to cause closing movement of switch A' including a grounded magnet-including conductor j having contacts 1 1 arranged each side of contact 4 and between contacts 2 2 and in circuit-closer-bridging relation to the source-conductor, branches h' h'' having electro- 70 magnetic means to hold switches A A' in closed position, and means to break branch h'' at c'' including a grounded conductor k 75 having contacts 3 3 arranged one at each side of the other contacts and in circuit-closer-bridging relation to said source-conductor, conductors i and j having breaks normally closed by switches A' and A , respectively. 80

In testimony whereof I affix my signature in presence of two witnesses.

GEORGE JACKSON, JR.
